J.B. Reynolds,

Bench Plane.

Patented July 7. 1832.

71387 16 377
William B. Reynolds, of Chillicothe, State of Ohio.

Letters Patent.

The schedule referred to in these Letters Patent and making part of the same containing a description in the words of the said William B. Reynolds, himself of his improvement in the Double Iron Tilling Planes.

To all to whom these presents shall come.

Be it known that I William B. Reynolds of the Town of Chillicothe in the County of Belmont and State of Ohio, have invented a new and useful improvement in the double Iron Tilling Planes which I have given my improvement the name of Double Iron Tilling Planes, and that the following is a full and exact description of the construction of the said plane, as invented and improved by me. With reference to the draught by figures and letters, a. is the iron bit which lies in the back of the mouth of the plane which contains the bit mortise about five eights wide and four inches long, which mortise starts at the upper edge of the bit, f. is the screw that lays in the mortise which regulates the cap iron, b. is the cap plate that lays on the iron that contains the bit mortise, which is made out of a flat rolled steel about one eighth of an inch thick, bevelled off at the lower end, and f. close to the lower end of the cutting part of the bit that contains the bit mortise, and lets down which the cap is regulated by the screw, f. which is a side view the screw f. is inserted through a plate in the form of a staple D. the width of the bit mortise in plate on the length of the staple each foot that the screw is inserted is about one inch and three fourths apart, the lower part is a strong screw out to insert the screw through for the cap to move up and down, to regulate the cap to the cutting part, of the plate a. the staple is let up through the cap plate with a square mortise which may be fastened by two tops or may be riveted to an iron the same, with a guard that is below the back of the mouth of the plane behind the iron that contains the bit mortise, it is made in the form of a square with a screw let through the lower end about one inch long one fifth thick with a head about three eights of an inch diameter with a hole cut in to come with a screw rivet to be fastened to the lower part of the staple D. which is fastened through the cap plate.

7158X

D. which it helps the bit when planed in the plane from setting too deep, it is
the screw in the guard to, about a fourth thick one inch long, head about three
eighths diameter with a notch cut in a screw driver to turn with a screw driver
as a guard against the loose end of the staple D, that is fastened to the cap plate
for the purpose of regulating the depth of the set of the bit when the plane is in use, the gauge
to, is about five eighths, and one fourth thick, then wider and one fourth long at the base
and where the screw is let through, is about three eighths thick, for the purpose of
strength, it is let into the back of the mouth of the plane, about three fourths deep
exactly in the center of the mouth, and secured fast by two wood screws, P. 2. the
bit screw, it is made exactly the length of the slot mortise about one fourth thick,
with a thick strong head three eighths diameter, with a notch to receive the screw
driver to regulate the cap. The handle is cut up from the front about two inches
and a half, and slipped through a smooth hole in the upper part of the staple D,
to the lower end at P. 6, which a strong thread is cut through to secure the handle
by turning it the cap many up and down to regulate the set of cap plate when
^{the cap is not of the same size as the bit} placed together, in the plane ready for work. P. 4 is a side view of cap plate, staple
and set screw to show the plan they are united together. June the 2^d 1832.
